Application filed May 31, 1892. Serial No. 435,073. Term of patent 3½ years.

To all whom it may concern:

Be it known that I, GEORGE H. WILCOX, of Meriden, in the county of New Haven and State of Connecticut, have invented a new 5 Design for a Cigar-Tray; and I do hereby declare the following, when taken in connection with accompanying drawings, to be a full, clear, and exact description of the same, and which said drawings constitute part of this 10 specification, and represent, in—

Figure 1 a top view, and Fig. 2 a longitudinal section.

This invention relates to a design for a tray for containing cigars or cigarettes, and which 15 has match-holders combined therewith, the design consisting in the configuration and ornamentation of the tray, as shown in the accompanying illustration. The tray proper is in the form of a parallelogram, the angles 20 represented as slightly rounded with flaring sides, the ends of the tray represented as ris-

ing above the sides, the edge ornamented by the representation of scroll-work springing from the raised ends and running around the sides, the outer edge conforming to the shape 25 of such ornamentation. The ornamentation is alike at both ends and at both ends the ornamentation continues of like character, rising from the ends and surrounding the match-holders, alike at both ends, all as shown in 30 the accompanying illustrations.

I claim—

The design for a cigar-tray, as described and shown in the accompanying illustration.

In testimony whereof I have signed this 35 specification in the presence of two subscribing witnesses.

GEORGE H. WILCOX.
